SAFETY RAZOR

Joseph Muros, Cambridge, Mass., assignor to Gillette Safety Razor Company, Boston, Mass., a corporation of Delaware

Application November 4, 1935, Serial No. 48,165

12 Claims.

(Cl. 30—61)

This invention relates to safety razors of the type employing hinged cap sections in combination with a guard or other blade-supporting member movable with respect to the cap sections to clamp a flexible blade in position for shaving. An example of such a razor is to be found in my own prior Patent No. 1,992,038.

An object of the present invention is to simplify the mechanism for swinging the cap sections to and from their closed position and for moving the blade-supporting member to flex and clamp the blade. The invention contemplates a novel safety razor structure which may be manufactured with advantage under economical conditions and which is compact in arrangement and convenient in operation. As herein shown, the guard is utilized as a blade-supporting member and is arranged for free movement upon the handle of the razor. The handle is provided with a cross-bar constructed and arranged to have a multiplicity of functions in the razor. In the first place, it is designed to engage the blade aperture and so position the blade in the razor. It is also utilized as a support for the hinged or pivotally mounted cap sections. Further, it is so related to the guard as to hold the latter against turning movement in the razor and, finally, it is provided with transverse arms which act as a blade carrier and support the blade in a position above the guard when the latter occupies its lowermost position and the razor is opened for cleaning or replacing the blade.

Another feature of the invention consists in a nut arranged to work up and down upon the handle of the razor and to carry the guard, having a swivel connection therewith and serving to move it in one direction or the other when turned by the user. Since the guard is otherwise free to swing transversely it is arranged to interlock with the cross-bar in a manner which holds it always in a predetermined angular position while permitting it to move up and down for clamping or releasing the blade.

These and other features of the invention will be best understood and appreciated from the following description of a preferred embodiment thereof, selected for purposes of illustration and shown in the accompanying drawings, in which:

Fig. 1 is a view in perspective of the razor in closed condition and on an enlarged scale;

Fig. 2 is a view of the razor head in vertical cross-section on the same scale;

Fig. 3 is a view of the razor head in cross-section on the plane 3—3 of Fig. 2;

Fig. 4 is a view similar to Fig. 2 but showing the guard in a partially lowered position;

Fig. 5 is a view of the razor head in open condition;

Fig. 6 is a cross-sectional view corresponding to Fig. 2 but showing the razor in open condition;

Fig. 7 is a fragmentary view in cross-section on the line 7—7 of Fig. 2, and on a still larger scale;

Fig. 8 is a similar fragmentary view in elevation of a modified detail of construction, and

Fig. 9 is a fragmentary view in perspective showing a portion of one of the cap sections modified as in Fig. 8.

In its general organization the safety razor herein shown includes a handle having a cross-bar, upon which two cap sections are pivotally mounted, and a guard member which is freely movable upon the end of the handle upwardly into blade-clamping position and which has operative connections with the cap sections for swinging them toward and from blade-clamping position.

More specifically the razor includes a solid elongated handle 10 shouldered to form an end portion 11 of reduced diameter which is threaded throughout the major part of its length and forked at its extreme end to receive a cross-bar 12, herein shown as formed by folding longitudinally a sheet metal blank. The cross-bar 12 is provided centrally with a short downwardly extending stem and this is perforated to receive a pivot pin 13 which supplies a rocking mount at a fixed height in the end of the reduced portion for the cross-bar. The cross-bar 12 extends equally upon opposite sides of its pivoted pin. Its ends are offset downwardly and bent to form outwardly and oppositely extending transverse arms 15. Between the outer ends of each pair of arms 15 is pivotally mounted one of the co-operating cap sections 16. The cap sections 16 themselves are elongated transversely convex, hinged or pivoted members arranged to swing freely from closed position shown in Fig. 1 to the open position shown in Figs. 5 and 6. Each of the cap sections 16 has a pair of arms 17 which are connected to the transverse arms 15 of the bar 12 and these arms afford a space for the edge of the blade to pass out laterally beneath the cap sections and above the guard fingers.

The pivotal connection between the arms 15 and the cap sections 16 is shown on a larger scale in Fig. 7 from which it will be noted that the material of the transverse arms is merely forced inwardly to form a trunnion in an opening drilled

50

55

in the material of the adjacent cap section arm 17. The depressions in the arms 15 caused by the formation of these trunnions is indicated by the reference character 19. In addition the arms 5 17 of the cap sections are each provided with a short out-turned lug 18 disposed at substantially 90° to its associated arm and these lugs form a part of the operative connection which is utilized 10 to swing the cap sections as will be presently explained.

The upper reduced end 11 of the handle is provided with a circular nut 22 threaded upon the stem 11 and recessed at its lower end to receive the shoulder of the handle 10. The nut 22, therefore, fits freely but snugly upon the enlarged portion of the handle 10 at its lower end and flares somewhat upwardly from this point for artistic purposes and also to supply a gripping surface which may be conveniently engaged by 20 the user in rotating the nut.

The guard 23 is herein utilized as a blade-supporting and positioning member and also, as already intimated, it has operative connections for moving the cap sections. The guard 23 is of a 23 length to fit freely between the transverse arms 15 and is equipped at its opposite edges with guard teeth 24 of the usual construction. The endmost tooth at each side of the guard is provided with an outwardly extending shoulder 25 which 30 underlies one of the arms 17 of the cap sections. The guard is provided also at each end with a pair of downturned lugs 26 which travel just inside the transverse arms 15 of the cross-bar 12 and with an elongated centrally disposed depression 35 in the general shape of a diamond.

One form of blade 30 suitable for use with the 40 razor of my invention is shown in the various figures of the drawings. This blade is provided with oppositely disposed cutting edges and is centrally apertured to receive the cross-bar 12 which also acts as a blade-locating device and accurately determines the position of the blade in the 45 razor. The corners of the blade are recessed thus forming in the blade centrally disposed unsharpened elongated portions which overlie the arms 15.

The guard 23 is provided with a central recess of sufficient size entirely to clear the reduced end portion 11 of the handle and to receive a flanged ring formed in the upper end of the nut 22 and 50 constituting a swivel connection with the guard.

The nut 22 is therefore adapted to be worked up and down upon the reduced end of the handle carrying the guard 23 with it. The guard is vertically slotted at its ends to receive the downwardly offset ends of the cross-bar 12 and is by this means held positively against turning in the razor. The position of the out-turned lugs 18 on the arms of the cap sections with respect to the endmost teeth 24 of the guard is such that when the 55 guard is lowered these lugs are engaged by the underside of the endmost teeth of the guard and rocked inwardly upon their pivots carrying the cap sections outwardly.

Assuming now that the razor is in closed blade-clamping position as shown in Fig. 1 and that the 60 user desires to open the razor for the purpose of cleaning or replacing the blade, he has then only to turn the nut 22 toward the left as seen in the drawings causing it to travel downwardly with 65 the guard 23, releasing the clamped blade 30 from its curved position and permitting it to reassume a flat condition as shown in Figure 4. During this initial part of the downward movement of the nut the guard teeth 24 are moved downwardly just into contact with the out-turned lugs 70

18 of the cap section arms. Further downward movement of the nut and guard from this position causes the guard teeth 24 to rock the lugs inwardly approximately 90° and at the same time swinging the cap sections 16 away from each other and into the wide open position as shown in Fig. 6. In its final movement the guard passes below the arms 15 leaving the blade resting thereon and the arms thus have the function of a blade carrier. The blade 30 is thus fully exposed 10 and may be conveniently removed from the guard. After replacing the blade the razor may be closed by turning the nut 22 toward the right, lifting the guard and causing the shoulders 25 to swing the cap sections again into their closed position. 15 Then, in the further upward movement of the guard, the blade 30 is forced against the concave side of the closed cap sections 16 and clamped in a transversely curved condition as shown in Fig. 2, ready for shaving.

A constructional modification of the cap section elements of the razor is shown in Figs. 8 and 9. In this instance, the cap sections 36 are provided with arms 37, each of which has in its inner face an elongated recess 38. The endmost teeth 25 of the guard 39 are modified to the extent of presenting a cam projection 40, which plays in the recess 38 as the guard is raised and lowered, and with an outwardly extending shoulder 41 arranged to underlie an arm 37 when the cap sections are opened. When the guard is lowered in the razor the projections 40 engage the bottom of the recesses 38 and act to swing the cap sections 36 outwardly into open position. Thereafter, when the guard is raised, the shoulders 41 engage the arms 37 and lift the cap sections back to closed position. In both instances it will be noted that the cross-bar 12 has the triple function of carrying the cap sections, of positioning the blade in the razor, and of holding the guard in fixed 40 angular position as it is raised or lowered by the nut 22.

Having thus described my invention what I claim as new and desire to secure by Letters Patent is,—

1. A safety razor comprising a handle having a threaded end portion, cap sections supported from the end of the handle for pivotal movement, a nut arranged to work up and down upon the threaded portion of the handle, and operating 50 connections between said nut and the cap sections.

2. A safety razor comprising a solid handle having a threaded end, a cross bar mounted on the end of the handle, cap sections pivotally supported by the cross bar, a nut arranged to work up and down upon the threaded portion of the handle, and operative connections between said nut and said cap sections.

3. A safety razor comprising a handle having a reduced and threaded end portion, cap sections 60 pivotally supported from the end of the handle, a nut arranged to work up and down upon the handle, a plate carried by the nut and held against turning movement, and operative connections between said plate and the cap sections.

4. A safety razor comprising a handle having a cross bar at one end, cap sections pivotally mounted on the cross bar, a nut threaded upon the handle, a guard carried by the nut, having a swivel connection therewith, and being held 70 against turning by said cross bar, and operative connections between the guard and cap sections.

5. A safety razor comprising a handle having a cross bar at one end, cap sections pivotally carried by the cross bar, a nut threaded upon the 75

5 handle beneath said cross bar, a guard apertured to receive a portion of the cross bar and connected to the nut for movement therewith, and connections between the guard and cap sections for swinging the latter.

6. A safety razor comprising a handle having a reduced threaded end portion, a nut arranged to work up and down thereon, a guard perforated for the passage of the end of the handle and having a swivel connection with the nut whereby the guard may be moved up and down on the handle by rotation of the nut, cap sections supported from the end of the handle above the guard, and operative connections between the guard and cap sections.

7. A safety razor comprising a handle with a threaded end portion having a nut thereon, a guard freely movable upon said end portion and resting upon said nut, a cross bar carried by the end of the handle above said guard, connections between the cross bar and guard to hold the latter against turning, and cap sections arranged to cooperate with the guard.

8. A safety razor comprising a handle having a reduced and threaded end portion, a cross bar mounted in the handle and having down-turned ends, a guard freely movable on the reduced end of the handle and apertured to receive the down-turned ends of the cross bar, a nut movable upon the threaded end of the handle beneath the guard, and cap sections hinged to the cross bar.

9. A safety razor comprising a handle having a

threaded end, a cross bar carried at a fixed height thereby and having its ends offset downwardly and provided with out-turned arms, a nut rotatable on the threaded handle end, a guard resting upon the nut and movable in the space between said arms, and cap sections carried by said arms.

10. A safety razor comprising cap sections, a guard, and a handle extending freely through the guard and having a cross-bar carried at a fixed height thereon, the cross-bar serving both to carry the cap sections and engage the guard to hold it against turning.

11. A safety razor comprising cap sections, a guard, an apertured blade, and a handle extending freely through the guard and having a cross- 15 bar carried at a fixed height thereon, the cross-bar being arranged to position the blade by engaging its aperture, to carry the cap sections and to engage and hold the guard against rotation in the razor.

12. A safety razor comprising cap sections, a guard, a handle extending freely through the guard and having a cross-bar with transverse arms carried at a fixed height on the handle, a blade apertured to receive the cross-bar and rest 25 upon the guard, and means for raising and lowering the guard, the cross-bar being arranged to support the cap sections and to lift the blade off the guard when the guard is moved to its lower-most position.

JOSEPH MUROS.
